WINCH

John J. Low, Los Angeles, Calif., assignor to
 Kay-Brunner Steel Products, Inc., a corpora-
 tion of Delaware

Application December 18, 1935, Serial No. 55,036

9 Claims. (Cl. 254—185)

My invention relates to winches for hoisting and pulling devices positioned at a distance thereto and capable of operation by cables. It has particular reference, although not necessarily, to winches adapted for attachment to tractors to be carried and operated thereby for actuating excavating devices of roadway excavating machines towed by the tractors, and to permit complete control of the winches by the operators of the tractors.

It is a purpose of my invention to provide a winch embodying a sheave and cable system by which the various devices to be actuated by the cables can be individually operated and a fair lead from the winch to each device constantly maintained irrespective of the angular position of the winch with respect to the device.

Another purpose of my invention is the provision of a winch having a driving mechanism including a power take-off mechanism which permits the winch to be applied to and operated by any conventional form of tractor, and irrespective of the direction and rotational speed of the transmission shaft of the tractor, so that the rotational speed of the winch drums can be made constant to linearly move the cables at such a predetermined speed as to insure safe operation of those devices adapted to be actuated by the cables.

Another purpose of my invention is the provision of a support for a winch by which the winch can be attached to and rigidly supported on any conventional form of tractor and with the winch driving mechanism sustained in proper operative relationship to the transmission shaft of the tractor.

Another purpose of my invention is the provision of a clutch and brake mechanism which permits the positive driving of, the absolute free rotation of, and the secure locking of the winch drums when and as required.

Another purpose of my invention is the provision of a winch having two drum units and a single driving mechanism therefor so correlated to the drums as to permit the winch to be used as a single or double drum unit and to allow such optional use on a tractor as conditions may require.

I will describe only one form of winch embodying my invention, and will then point out the novel features thereof in claims.

In the accompanying drawings:

Fig. 1 is a view showing in side elevation one form of winch embodying my invention in applied position on the rear end of a conventional form of tractor.

Fig. 2 is a view similar to Fig. 1 but without the upper drum unit.

Figs. 3 and 4 are enlarged sectional views taken on the lines 3—3 and 4—4 of Fig. 1.

Fig. 5 is a sectional view taken on the line 5—5 of Fig. 3.

Fig. 6 is an enlarged vertical sectional view taken on the line 6—6 of Fig. 1.

Fig. 7 is an enlarged view showing the winch in front elevation removed from the tractor and 10 with the support attaching bolts in section.

Figs. 8 and 9 are vertical sectional views taken on the lines 8—8 and 9—9 of Fig. 6.

Fig. 10 is a vertical sectional view taken on the line 10—10 of Fig. 7.

Fig. 11 is a semi-diagrammatic view showing in perspective the driving mechanism for the winch drums and a portion of the power take-off mechanism.

Fig. 12 is an enlarged sectional view taken on the line 12—12 of Fig. 1.

Fig. 13 is a detail perspective view showing the attaching support by which the winch is secured on the tractor.

The winch as herein illustrated comprises a 25 lower housing H and an upper housing H¹ superimposed on the former. As the two housings are identical in construction and the elements contained therein the same, only the lower housing and its elements will be specifically described, but 30 like numerals bearing the exponent "a" have been employed on the drawings to designate corresponding parts of the upper housing and the elements contained therein.

The lower housing is made up of two end sections 15 and 16 and an intermediate section 17. Each end section 15 or 16 is made in two parts, as best shown in Fig. 6, and the outer part of each section for the lower housing is secured to the corresponding part of the same section of the 40 upper housing by the provision of flanges 18 on the sections through which bolts 19 extend.

At the front or tractor side of the housings the three sections are secured in definite spaced relation to each other by two angle bars 20 and 45 21 and a flat bar 22. While at the rear side the sections are similarly secured by three T-bars 23 arranged one above the other. Thus it becomes apparent that the several bars constitute a frame which rigidly secures the several sections of each 50 housing together. The frame is supplemented by shafts, to be described hereinafter, which lend such additional rigidity to the frame as to produce housing structures of the requisite strength. Each intermediate housing section 17 is formed 55

- with a web 24 (Fig. 6) having a central hub 25 through which extends a shaft 26. Each shaft is enlarged where it extends through the hub, and at this point it is keyed to the hub to prevent rotation thereof. Two winch drums 27 and 28 are rotatably mounted on the shaft 26 by roller bearings 29 and 30, respectively. There are two such bearings for each drum contained in collars 31 and 32, respectively, formed integral with internal webs 34 and 35, respectively, of the drum. The inner bearings are retained in place by the hub 25, and the outer bearings by nuts 36-36. This arrangement permits of either drum to be removed or applied lengthwise of the shaft 26 through the respective end of the housing.
- Each winch drum 27 or 28 is provided at its outer end with two annuli 37 and 38 the confronting peripheries of which are shaped to provide a double face female clutch member. A male cone 39 having faces corresponding to those of the female member, is movable to engage and disengage the female member. This male cone is secured to a gear 40 by cap screws 41, and the gear in turn has an integral hub 42 which is rotatable on a sleeve 43 between collars 44 and 45. The collar 44 is threaded on the sleeve, while the collar 45 is formed integral with the sleeve and shaped to receive and support a ball bearing 46.
- At the inner side of the collar 45 the sleeve 43 is splined to the shaft 26 by a feather 47 so that the sleeve is free to slide on the shaft but cannot rotate relative thereto. To the outer side of the collar 45 the sleeve has a threaded connection 35 with an actuating sleeve 48 rotatable in and projecting from a collared opening 49 in the housing section 15 or 16. The sleeve 48 is rotatable on rings 50 secured on the shaft 26 by nuts 51, and clamped to the sleeve is a split collar 52 on one end of an arm 53.
- From the preceding description, it will be clear that the male cone 39 of the double cone clutch is operable to engage or disengage the winch drum to connect or disconnect the gear 40 there-45 to by rotation of the sleeve 48 in one direction or the other by operation of the arm 53. Thus the sleeve 43 is moved outward or inward on the shaft 26 to effect the requisite lateral movement of the gear 40 necessary to actuate the male cone.
- In this manner the clutch is operable to effect a driving connection between the gear and the drum. Aside from the structural simplicity of this clutch its operation is rendered positive by reason of the mounting of the gear hub 42 be-50 tween the collars 44 and 45 to insure positive movement of the gear with shifting of the sleeve 43 so that the male member of the clutch will be moved completely out of or into engagement with the female member. Thus is eliminated the possibility of the clutch dragging when in disengaged position.
- Manifestly, the two lower drums 27 and 28 and their appurtenances constitute one winch unit, and the upper drums 27^a and 28^a and their ap-65 purtenances constitute another winch unit. The gears 40 are adapted to be driven positively by a suitable mechanism to be described hereinafter. The upper gears 40^a mesh with the lower gears to be driven by the latter and to effect operation of the upper drums when the clutches therefor are engaged. Obviously, the width of the gear teeth of all the gears is such as to maintain the gears in mesh irrespective of the lateral movements thereof necessary to the operation of the clutches.
- As there is one actuating arm 53 for each

clutch, there is provided also one operating lever 54 for each arm. This winch being particularly adaptable to tractors for control by the operator of the tractor, each lever is mounted and shaped to extend upwardly and forwardly from the front side of the winch to provide an elongated handle 55 which is positioned at one side of the driver's seat, as shown in Fig. 1. As best shown in Fig. 7, each pair of levers is fulcrumed on the flat bar 22 by a bolt 56, and the short arm 57 of the lever 10 is operatively connected to the respective arm 53 by a link 58.

The operating levers 54 and 54^a, in addition to providing means for operating the clutches, provide means for actuating external contracting 15 brakes, one for each winch drum to secure the latter against rotation at the will of the operator. The four brakes are identical in construction, only the bands and their operating mechanisms for the upper brakes are reversely arranged 20 with respect to those of the lower brakes.

As best shown in Figs. 6 and 9, the annulus 37 of one winch drum has an outer periphery 59 concentric of the drum axis which constitutes a brake drum to be engaged by a brake band 60. 25 One end of this band is anchored to a bolt 61, and the other end operatively connected to the short arm of a bell-crank lever 62 fulcrumed on the housing as at 63. A spring 64 connected to the housing by a hook 65 and to the lever 62 by an eye bolt 66, serves to yieldably urge the lever to a position in which the band embraces the drum to effect a brake application. By means of a cam 67 rotatably supported in a bracket 68 secured to the lower angle bar 20 35 (Fig. 1), the brake lever 62 can be actuated against the action of the spring 64 to effect a brake release of the band with respect to the drum. As the winch drum is adapted when paying out a cable wound thereon, to rotate in a clockwise direction as when viewed in Fig. 9, the band 60, by reason of its mounting, will be actuated by such drum rotation to grip the drum and effect a brake application. In this manner the 40 brake is rendered self energizing.

The cam 67 for the brake lever is operable to effect a brake release by the corresponding clutch arm 53, and it is connected thereto by a lost-motion connector C and a link 69. The connector is shown in Figs. 3 and 4 as comprising a pair of clevises 70 and 71, one connected to the link 69 by a pin 72, and the other connected to the arm 53 by a pin 73. Sleeves 74 and 75 are formed on the respective clevises 70 and 71, and a rod 16 is movable in the sleeve 74 and provided with a retaining head 71. The other rod end is threaded in the sleeve 75 and adjustably retained there-55 in by a nut 78.

Similarly, the clutch arm 53^a for each of the upper clutches is connected to its cam 67^a by a 60 lost-motion connector C¹ identical in construction to the connector C except the head 71 is dispensed with and the plain end of the rod 16^a is adapted to abut a cross web 79 as it is moved upwardly.

In constructing the connectors C and C¹ to provide lost-motion between the clevises, limited movement upwardly of the clutch arms 53 and 53^a from the neutral position is permitted before the 70 cams 67 and 67^a are actuated to effect release of the brakes. In this manner the necessity of fine adjustments of the parts concerned, is eliminated and the operator is given sufficient latitude in operation of the levers 54 and 54^a to effect complete 75

engagement or disengagement of the clutches before the brakes are released or applied.

In the operation of any one clutch and the companion brake, the arm 53 normally occupies a neutral position in which the clutch is released and the brake applied by the spring 64, thus securing the winch drum against rotation. By moving the arm 53 downward or in a clockwise direction as when seen in Fig. 1, the clutch is engaged to drive the drum. Manifestly, the upper drums are driven in the opposite direction from that of the lower drums. Such drum rotation, in each instance, automatically releases the brake against the action of the spring so that the drum is free to be driven. When the arm 53 is elevated, that is, rotated counter-clockwise from the neutral position, the clutch remains disengaged but the brake is released by operation of the cam 67 so that a cable wound on the drum 20 can be unwound therefrom as required.

Referring now to Figs. 1 and 19 the winch drums 27 and 27^a, as well as the drums 28 and 28^a which are not visible in these figures, have cables 79 and 79^a, respectively, wound reversely thereon. For supporting these cables so that as extended from the drums rearwardly of the winch housings they will at all times individually maintain a fair lead with respect to any mechanism or devices which they are pulling or hoisting, and 30 to cause the cables to be properly wound on the drums, sheave systems are provided.

The sheave system for each pair of cables 79 and 79^a comprises two lower sheaves 80 and 81 and two upper sheaves 80^a and 81^a. As the arrangement and supports for one pair of sheaves are identical to those for the other, with the single exception of one being inverted with respect to the other, a description of one will suffice for both. Like numerals bearing the exponent "a" are employed on the drawings to designate corresponding parts of the supports for the upper sheaves.

The lower sheave 80 is rotatably mounted in a housing 82 which is formed integral with and disposed laterally of a support 83. This support is elongated and tubular and it is rotatably supported at its ends in bearings 84 and 85. The upper bearing 84 surrounds a hub 86 secured within the horizontal web of the lowermost T-bar 23, 50 while the lower bearing 85 surrounds a solid hub 87 secured in a U-shaped bracket 88 bolted to and depending from the same bar 23.

The upper sheave 81 is rotatably mounted in a housing 89 formed integral with a support 90 of the same construction as the support 83 and disposed between the lowermost and intermediate bars 23. Similarly, bearings 91 and 92 surround, respectively, the lower hub 86 and an upper hub 93 in the intermediate bar 23 to rotatably mount 60 the support 90 between the bars. The hub 93 is common to the upper and lower ends, respectively, of the supports 90 and 90^a.

The cable 79 as extended from the bottom of the drum 27 passes under the sheave 80, then upwardly through the support 83 and hub 86, and finally over the sheave 81. The housings 82 and 89 are constructed to aid in confining the cable on the sheaves, but as a further aid the supports are provided with projections 94.

70 It is characteristic of the two supports 83 and 90 that they are vertically aligned so that the two sheaves revolve about the same vertical axis. By this manner of mounting the sheaves the sheave 80 is free to assume the positions necessary to cause proper spiral winding of the cable

on the drum, while the sheave 81 can revolve through an angle of 180 degrees to maintain a fair lead of the cable in respect to any mechanism or devices to which it is attached. It is important to note that the stretch of cable between the sheaves is coaxial with the axis of the supports so that there will be no lateral displacement of the cable and in order that a fair lead will be maintained in any angular position of adjustment of either support.

Referring now to Figs. 7, 8, and 11, the gears 40 for the drums 27 are positively driven by a mechanism which is characterized by parts capable of being interchanged to compensate for variation in both direction and rotational speed of 15 the transmission shaft of the tractor from which power is taken to propel the mechanism. Thus, the rotational speed of the winch drums and resultant linear speed of the cables can be made constant to operate the devices to be pulled or 20 hoisted by the cables, at a predetermined speed. The invention also includes a power take-off mechanism and a mounting means therefor which permit such mechanism to be applied to the transmission shaft of any conventional form of 25 tractor and driven thereby to, in turn, actuate the driving mechanism for the winch drums.

The driving mechanism is situated at the forward side of the winch housings to permit of its being operatively connected to the power take-off 30 mechanism mounted on the rear end of the tractor. As shown in Fig. 11, this driving mechanism comprises a countershaft 95 on the ends of which are gears 96 meshing with the respective gears 40. The gears 96 are contained within the lower 35 housing H with the shaft disposed exteriorly thereof where it extends between bearings 97 secured to the housing. A third gear 98 is fixed on the shaft 95 to mesh with a similar gear 98^a fixed on a jack shaft 99 journaled in suitable 40 bearings contained in a housing 100 bolted to the housing H. The ends of the shaft 99, which project from the housing 100, are screw-threaded to receive and secure to either shaft end a double sprocket wheel 101. Over this sprocket wheel is 45 trained a double sprocket chain 102 for connection to a similar wheel which is positively driven to drive the entire mechanism.

When the winch is mounted on the rear end of the tractor the chain 102 is positioned to engage 50 a double sprocket wheel 103 which constitutes a part of the power take-off mechanism. As shown in Figs. 11 and 12, this mechanism comprises a driven shaft 104 journaled in two bearings 105 secured, respectively in collars 106 on the 55 inner sides of two end plates 107 and 108. These plates are removably secured to and constitute the ends of a housing 109 for the shaft 104 except where the latter extends through the plate 107 to project from the housing to permit attachment of 60 a sprocket wheel 103.

For securing the housing 109 to the rear wall 110 of the tractor shown in Fig. 1, a plate 111 is bolted to the housing and to the tractor wall, as shown in Fig. 12. This plate is constructed to 65 permit extension therethrough of a driving shaft 112 operatively connected to the shaft 104 by beveled gears 113 and 114. A pocket 115 in the plate receives suitable bearings 116 for the shaft, and this pocket is closed by a cover plate 117 bolted to the plate 111 and which is designed to snugly fit within the usual opening provided in the wall 110.

From the cover plate the shaft 112 projects through the tractor wall for connection by an 75

adapter shaft 119 to the rear end of the transmission shaft 120 of the tractor. As shown in Fig. 12, the shaft 119 is connected to the shafts 112 and 120 by splined joints 121.

5 By detaching the plates 107-108 from the housing it is possible to reverse the position of the shaft 104 with respect to the shaft 112, as indicated in dash lines in Fig. 12. Such shaft reversal positions the sprocket wheel 103 to the 10 opposite side of the housing to place the gear 113 again in mesh with the gear 114. Thus, if the transmission shaft is rotating in the opposite direction to that necessary to drive the drums 27 and 28 in a clockwise direction as when viewed in 15 Fig. 11, then by reversing the shaft 104 as described, proper directional driving of the drums can still be obtained. It will of course be understood that mounting the wheel 101 and chain 102 on the other end of the shaft 99 is also necessary 20 to this accomplishment.

It is desirable to drive the winch drums at a speed sufficiently low to effect safe operation of the devices which the cables actuate. Rotational speed of the tractor transmission shafts naturally 25 vary, and to compensate for such variation in a manner to rotate the drums at a preselected safe speed the wheels 101 and 103 can be replaced by larger or smaller wheels as the case may demand to drive the jack shaft 99 at that speed 30 necessary to rotate the drums at the preselected speed.

The entire winch structure and its accompanying driving mechanism can be attached to the rear tractor wall 110 in the elevated position 35 illustrated in Fig. 1, by means of an attaching support characterized by its adaptability to the rear wall of any conventional form of tractor. As best shown in Fig. 13, this support comprises a pair of brackets 122 having lower ends formed 40 with pads 123 bolted to the tractor wall 110, and upper ends formed with ears 124 in which the ends of a tubular cross bar 125 are snugly received.

Another pair of brackets 126 have ears 127 receiving the bar 125, and these brackets are curved rearwardly and secured by bolts 128 (Fig. 7) to the flat bar 22. A single bracket 129 is secured at its lower end to the tractor wall 110 by bolts 130, and at its upper end to the bar 20 by bolts 50 131. This bracket 129 is disposed midway between the brackets 122 and 126 so that it coacts therewith in rigidly supporting the entire winch in fixed position on the rear wall of the tractor.

Although the invention has been thus far described as comprising two winch units, it will be manifest from the relationship and construction of the two units that the upper unit and its appurtenances can be removed completely from the lower unit without affecting operation of the latter, and thus the winch is reduced to a single unit. To cover the open top of the housing H a plate 132 (Fig. 2) is provided having at its forward edge an upstanding flange 133 braced along its length by integral webs 134.

65 With removal of the upper housing H¹, it is necessary to remove the flat bar 22 with the levers 54 and 54^a and remount the levers 54 on the flange 133. Also, the brackets 122 of the attaching support have to be rebolted to the flange 133.

70 In Fig. 2 the sheaves for the cables are shown reversely disposed or inverted from the position shown in Fig. 1 for the purpose of elevating the lower sheave 81 to provide ample clearance for the draw-bar (not shown) of a tractor where such bar is at a relatively high elevation.

From the preceding description of my invention taken in conjunction with the accompanying drawings, it will be manifest that I have provided a winch characterized by the relationship and detachability of certain of its parts to form a single or double winch unit, and whereby two or four winch drums are provided to permit operation at a distance of as many devices by their respective cables; and the identity and resultant interchangeability of its parts to simplify manufacture and facilitate assembly thereof.

My invention is characterized also by its adaptability to any conventional form of tractor to utilize the tractor for actuating the winch drums; placing the complete operation of each winch drum wholly within control of the operator of the tractor through the clutch and brake mechanisms provided; and maintaining at all times a fair lead of all cable irrespective of the angular relation of the winch drums or sheaves with respect to the devices operated by the cables.

I claim:

1. A winch, comprising; a housing having end sections and an intermediate section spaced from the end sections; a frame for fixedly securing the sections together; a shaft within the housing, spanning the sections and fixed to the intermediate section against rotation; and drums so journaled on the shaft as to be exposed between the housing sections, said end sections each being in two parts one detachable from the other to permit the shaft and drums to be inserted or withdrawn from the housing through the end sections.

2. In a winch; a housing; a shaft fixed therein; a drum journaled on the shaft; a clutch member fixed on the drum; a sleeve splined on the shaft; a gear journaled on the sleeve; a second clutch member fixed to the gear; driving means for the gear; and an element rotatable in the housing and having a screw-threaded connection with the sleeve so that by rotation of the element the sleeve will be moved to cause the clutch member carried by the gear to engage or disengage the other clutch member according as the element is rotated in one direction or the other.

3. In a winch; a shaft fixed therein; a drum journaled on the shaft; a clutch member fixed on the drum; a sleeve splined on the shaft; spaced collars fixed on the sleeve; a gear having a hub 50 journaled on the sleeve and embraced by said collars; a second clutch member fixed to the gear; and means mounted in the housing and operatively connected to the sleeve for so moving the latter on the shaft as to cause the collars to 55 actuate the gear to move the second clutch member into and out of engagement with the first mentioned clutch member.

4. A winch, comprising; two winch units including a pair of housings superposed, detachably secured one to the other, and the confronting sides of which are open; a pair of rotatable drums in each housing; gears, one for each of the drums normally disconnected therefrom and so arranged that the gears for the upper drums mesh with 65 the gears for the lower drums; means for driving the gears for the lower drums; clutches, one for each of the gears for operatively connecting the gear to the respective drum; brakes, one for each of the drums; and actuating mechanisms, 70 one for each clutch and its companion brake by which rotation of the respective drum can be controlled.

5. A winch, comprising; a pair of drums; means for rotatably supporting the drums in end to end 75

relation; two gears one for each of the drums; a shaft having a pair of gears fixed thereon and meshing respectively with the first mentioned gears; a third gear fixed on the shaft; a second shaft having a gear fixed thereon and meshing with the third gear; a driven sprocket wheel; coacting means on the second shaft and sprocket wheel by which the latter can be secured to either end of the second shaft; a driven shaft substantially parallel to the second shaft; a support for the driven shaft having parts so reversible as to permit reversing in position of the shaft in the support; a driving sprocket wheel fixed on one end of the driven shaft so that by reversing the shaft's position in the support the position of the sprocket wheel will be reversed likewise to correspond with a reversal in end position on the second shaft of the driven sprocket wheel; a chain operatively connecting the two sprocket wheels; a driving shaft; and gears so operatively connecting the driving and driven shafts that the driven shaft is rotated by the driving shaft irrespective of its position in the support.

6. In combination; a substantially vertical wall; a winch containing housing; a pair of brackets secured to said wall, extending upwardly thereof and spaced one from the other; a rod extending between and horizontally supported by said brackets; a second pair of brackets mounted on said rod and secured to said housing; and a bracket secured to said wall and extending upwardly thereof and secured to said housing between the second mentioned pair of brackets.

7. In combination; a substantially vertical wall; a winch containing housing; a pair of brackets having lower ends secured to said wall in spaced relation one to the other; ears on the upper ends of said brackets; a rod spanning the brackets having its ends secured in said ears; a second pair of spaced brackets having ears on one end through which said rod extends and secured to

said housing at the other end; and a single bracket situated midway between and below the second pair of brackets and secured at one end to said wall and at the other end to said housing.

8. In combination; a winch drum; driving means therefor; a clutch for connecting the driving means to said drum; an actuator for said clutch; an element adapted for releasing a brake for said drum; and an operative connection between said element and actuator comprising a pair of clevises; and a rod fixedly secured to one of the clevises and movably secured to the other clevis.

9. In combination; a winch drum; a brake actuating lever; a spring connected to said lever for urging the latter in one direction wherein a brake is adapted to be applied to the drum; a member operable to move the lever in the opposite direction wherein the brake is adapted to release the drum; a driving means for rotating the winch drum in one direction; a clutch for operatively connecting the driving means to the winch drum; a clutch operating arm; and a connector between said arm and member for actuating the latter by movement of the arm, said arm being pivoted to occupy a neutral position in which the clutch is disengaged and the brake applied, a second position in which the clutch is engaged and the brake free to be released, and a third position in which the clutch is disengaged and the brake released, said connector comprising at least two elements, and means for connecting said elements to allow movement of one element with respect to the other before the arm actuates the member so as to delay movement of the member by the arm, sufficiently to permit complete engagement or disengagement of the clutch before releasing or applying the brake.

JOHN J. LOW. 40
